ROLLER PRESSURE BAR FOR VENEER
LATHES

William J. Miller, Seattle, Wash., assignor to Elliott Bay Mill Co., Seattle, Wash., a corporation of Washington

Application March 31, 1947, Serial No. 738,456

2 Claims. (Cl. 144—213)

1

This invention relates to a roller pressure bar for a veneer lathe and the present invention is in the nature of an improvement on the double roller pressure bar disclosed in the prior patent application of myself and Alfred C. Johnson, Serial No. 623,706, filed October 26, 1945.

In the use of roller pressure bars of this type it is found that foreign matter in the nature of dirt, particles of wood and bark, pitch, sap and the like will get into the space around the rollers and interfere with the operation of these rollers.

An object of this invention is to improve the construction of roller pressure bars of this type by providing improved means for keeping the rollers clean and for discharging from the rollers small particles of foreign matter, such as dirt, bark, wood, pitch, sap and the like, that may get into said rollers.

A further object is to provide a double roller pressure bar having a log engaging pressure roller that bears against and has rolling contact with a driven backing roller, said two rollers having a cover member thereover that is provided with a plurality of spaced apart openings positioned above said two rollers so that foreign matter which gets into the space around said rollers will be discharged through said openings.

In the drawings Figure 1 is a fragmentary plan view of a double roller pressure bar constructed in accordance with this invention.

Fig. 2 is a view in cross section of the same taken substantially on broken line 2—2 of Fig. 1 and showing a fragment of a cap member in which the pressure bar is held.

Fig. 3 is a view in longitudinal section taken substantially on broken line 3—3 of Fig. 2, the cap member being omitted.

Like reference numerals designate like parts throughout the several views.

In Fig. 2 of the drawings 5 designates a fragment of the pressure cap of a veneer lathe. This cap 5 is provided, at its front edge and adjacent the position of a log 6 from which veneer is to be peeled, with an L-shaped notch 7 within which this pressure bar assembly is mounted.

This pressure bar assembly comprises a main supporting bar 8 adapted to rest in the L-shaped notch 7 and rigidly secured to the cap member 6 as by cap screws 9. The top side of the bar 8 is notched in stair step fashion, from its front edge rearwardly, to provide one shelf 10 on which a roller supporting plate 11, preferably of bronze, rests and another shelf 12 on which a strong heavy roller cap 13 rests. The cap 13 is rigidly secured to the bar 8 as by cap screws 14. The

2

bottom surface of the plate 11 preferably has a longitudinal groove 15 that fits over a longitudinal rib 16 on the shelf 10 to firmly anchor this plate 11 to the bar 8 and to prevent movement of said plate 11. A similar interlocking groove 17 and rib 18 are provided between the main supporting bar 8 and roller cap 13.

A roller backing bar 19, preferably of bronze, rests on the roller supporting plate 11 and is positioned against an upright wall 20 of the bar 8. The front side of the roller backing bar 19 is of concave shape to receive and support a driven-backing roller 21. A pressure roller 22 rests against the backing roller 21 and is held between the bottom plate 11 and rigid roller cap 13 and has its forward surface exposed for the purpose of engaging with a log. Preferably set screws 4 are threaded through the cap 13 and jam against the backing bar 19. These set screws 4 can be adjusted to vary the pressure of the cap member 13 on the rollers 21 and 22.

The upper surface of the roller supporting plate 11 and the lower surface of the rigid roller cap 13 are provided respectively with longitudinally extending arcuate grooves 24 and 23 which receive the backing roller 21.

The front edge portion of the cap 13 that covers the rollers 21 and 22 is rounded on top as shown in Fig. 2 and terminates in a relatively sharp downwardly curved lip 25 that rests on and engages with and helps to hold the pressure roller 22.

A plurality of escape openings 26 for foreign matter are provided at intervals in the cap member 13 above the rollers 21 and 22. Preferably these openings 26 are formed by the use of a grinding wheel by grinding two oppositely disposed intersecting arcuate recesses on opposite sides of the cap member 13. This undercuts the cap 13 and leaves relatively wide openings directly above the rollers 21 and 22 for the escape of foreign matter. It has been found that openings of the shape and form shown operate efficiently in the discharge of foreign matter. Bearing surfaces 27 for the rollers 21 and 22 are provided between the openings 26. Pressure bars of this type are usually from eight to ten feet long and it has been found satisfactory to provide discharge openings 26 at spaced intervals of about three inches. The backing roller 21 is driven in the direction indicated by the arrow in Fig. 2 and the pressure roller 22 is oppositely driven by frictional engagement with the backing roller 21 and by contact with the rotating log 6 from which veneer is being removed as by

a knife 28. Thus it will be seen that the contacting surfaces of the two rollers 21 and 22 are moving upwardly toward the openings 26. This tends to crowd foreign matter upwardly and out through the openings 26.

Obviously changes in this invention can be made within the scope and spirit of the following claims.

I claim:

1. Roller pressure bar means for a veneer lathe comprising a roller carrying bar having a roller receiving recess; a backing roller carried by said bar; a pressure roller carried by said bar and bearing against said backing roller, said pressure roller having an exposed peripheral portion adapted to engage a log from which veneer is to be removed; and a cover portion rigid with said bar extending over both of said rollers and having openings therein for the discharge of foreign matter from the space around said rollers.

2. Roller pressure bar means for a veneer lathe

comprising a roller carrying bar having a roller receiving recess extending longitudinally thereof a driven backing roller carried by said bar; a pressure roller carried by said bar and having peripheral contact with said backing roller and driven by said backing roller, the contacting portions of said two rollers being continuously movable in an upward direction when in operation said pressure roller having an exposed peripheral portion adapted to engage with a log from which veneer is being removed; and a cover portion rigid with said bar and extending over both of said rollers, said cover portion having a plurality of spaced apart openings positioned above the upwardly moving portions of said rollers for the discharge of foreign matter from the space around said rollers.
